(57)

CLAIM

The ornamental design for chair, substantially as shown and described.

DESCRIPTION

FIG. 1 is a perspective view of a chair according to a first embodiment of the present invention;

FIG. 2 is a front elevation view of the chair in FIG. 1;

FIG. 3 is a right-side elevation view of the chair in FIG. 1;

FIG. 4 is a rear elevation view of the chair in FIG. 1;

FIG. 5 is a left-side elevation view of the chair in FIG. 1;

FIG. 6 is a top plan view of the chair in FIG. 1;

FIG. 7 is a bottom plan view of the chair in FIG. 1;

FIG. 8 is a perspective view of a chair according to a second embodiment of the present invention;

FIG. 9 is a front elevation view of the chair in FIG. 8;

FIG. 10 is a right-side elevation view of the chair in FIG. 8;

FIG. 11 is a rear elevation view of the chair in FIG. 8;

FIG. 12 is a left-side elevation view of the chair in FIG. 8;

FIG. 13 is a top plan view of the chair in FIG. 8;

FIG. 14 is a bottom plan view of the chair in FIG. 8;

FIG. 15 is a perspective view of a chair according to a third embodiment of the present invention;

FIG. 16 is a front elevation view of the chair in FIG. 15;

FIG. 17 is a right-side elevation view of the chair in FIG. 15;

FIG. 18 is a rear elevation view of the chair in FIG. 15;

FIG. 19 is a left-side elevation view of the chair in FIG. 15;

FIG. 20 is a top plan view of the chair in FIG. 15; and,

FIG. 21 is a bottom plan view of the chair in FIG. 15.

The broken lines shown in the drawings represent boundaries of the claimed design and form no part thereof.
